UNITED STATES PATENT OFFICE.

ELLSWORTH A. HAWTHORNE, OF BRIDGEPORT, CONNECTICUT.

LIGHTING APPARATUS.

1,074,716.

Specification of Letters Patent.

Patented Oct. 7, 1913.

Application filed January 27, 1913. Serial No. 744,849.

To all whom it may concern:

Be it known that I, ELLSWORTH A. HAWTHORNE, a citizen of the United States, and a resident of Bridgeport, county of Fairfield, State of Connecticut, (whose post office address is 35 Spruce street, Bridgeport, Connecticut,) have invented an Improvement in Lighting Apparatus, of which the following description, in connection with the accompanying drawings, is a specification, like characters on the drawings representing like parts.

This invention relates to lighting apparatus and more especially, though not exclusively, to electric lighting apparatus for bicycles, motor-cycles or other vehicles.

The invention will be best understood by reference to the following description when taken in connection with the accompanying illustration of one specific embodiment thereof, while its scope will be more particularly pointed out in the appended claim.

In the drawings: Figure 1 is a plan view of a lighting apparatus embodying one form 25 of my invention; Fig. 2 is an end elevation thereof; Fig. 3 shows the same apparatus in sectional elevation on the line 3—3 in Fig. 1; and Fig. 4 is a sectional detail in plan taken on the line 4—4 in Fig. 3.

Referring to the drawings, I have there illustrated one form of the invention embodied in an electric lamp intended to be used as a tail light, more particularly for a bicycle or motor-cycle, and to display a rear 35 red light. As illustrated, such apparatus comprises a generally barrel-shaped shell or casing 1 adapted to receive a standard dry cell of cylindrical shape. The casing is embraced and supported by the band 3 clamped 40 to the arm 4, which latter is adjustably secured to the bracket 5. The bracket may be fastened to any appropriate part of a bicycle or motorcycle frame, as for example to the saddle post, so that the lamp will be 45 supported at the rear of and just below the saddle. At its rear side the lamp casing 1 is provided with a lamp holder consisting of the shell 6 fixedly secured to the casing 1 and containing the reflector 7 and threaded 50 lamp socket 8, the latter adapted to receive the threaded base of the miniature incandescent lamp 9. The front of the lamp holder is provided with a lens or glass front 10, herein in the form of a red jewel light 55 so that the light from the lamp 9 is reflected through the red glass. The glass front is

held in an annular ring 11 secured to the beaded or curved flanged portion 12, the latter having in its rearward face a pair of slots 13 which are of a suitable size to slip 60 over the pins 14 projecting radially from the holder 6. This provides means whereby the glass can be readily applied to a lamp holder by slipping it over the pins 14 and giving it a quarter turn. This also provides 65 means whereby it may be readily removed and replaced by a plain, uncolored glass front so that, when it is desired to use it as an exploring light, the lamp may be removed from the saddle post and the colored 70 lens quickly replaced by the plain one.

Connection is had to the lamp from one pole of the battery through the contact piece 15, the casing 1 and socket 9. From the other pole 16 of the battery, connection is 75 had to the lamp base through a spring contact member 17. The latter consists of a metallic spring clip held in suitable relation to the lamp socket by means of the metallic clasping member 18 (see Figs. 3 and 80 4), an intervening insulation of fiber 19, or other material, being provided to insulate the contact 17 from the lamp casing. The clasping member 18 is held fixed to the interior of the casing by any suitable 85 means. The upper end of the contact clip 17 is slotted to receive the tongue 20 of the hinged contact member 21, the latter being adapted to overlie the battery terminal 16 and being pressed thereagainst at 90 will by means of the screw 22 carried by the casing cover 23. The hinged contact member 21 carries the insulation strip to insulate the same from the screw 22. To withdraw the contact member 21 from the 95 battery terminal when the screw is retracted, the lip 20 is bent over and down about the end of the contact strip 17 so that when the screw is retracted it tends to lift the contact member 21 free from the battery 100 pole 16. The screw 22 is provided with a thumb piece 25 and is carried by the threaded button 26 secured to the cover 23. The latter is slotted at 27 (Fig. 2) to engage with the pins 28 so that it can be applied 105 to and withdrawn from the casing in the same manner as the lens holder.

The hinged construction described is a very advantageous one since the contact member 21 may be readily rocked to and 110 from its horizontal position with a minimum wear on the parts in making and

breaking the circuit and in the insertion and removal of battery cells. When in its horizontal position the flat back of the lip 20 is pressed by the resilient contact member 17 against the flat intervening insulation fiber 19 and thereby continuously and effectively tends to lift the contact member 21 out of engagement with the battery pole 16.

Through the use of a resilient contact piece 17 the lamp when screwed into its socket is brought against a resilient seat, thereby being prevented from unscrewing through the vibration or shaking of the lamp.

15 The described form of lighting apparatus provides a very small, compact lamp suitable for use as a rear bicycle light, while at the same time it is easily converted into an exploring light, as previously described.

20 While I have herein shown and described for purposes of illustration one specific form of the invention, it is to be understood that the same is not limited to the constructional details shown, but that extensive deviations

may be made therefrom without departing 25 from the spirit of the invention.

Claim.

An electric lamp for vehicles comprising, in combination, a casing adapted to contain a dry battery cell, a lamp holding socket, a 30 resilient contact member against which the lamp is adapted to seat when in said socket, said contact member being slotted, a second contact member having an end passing through said slot and bent over and about 35 said first contact member, providing thereby a hinged connection thereto having provision tending to lift said second contact member from a terminal of the battery, and means for applying said second contact 40 member to said battery terminal.

In testimony whereof, I have signed my name to this specification, in the presence of two subscribing witnesses.

ELLSWORTH A. HAWTHORNE.
